Primary Examiner — Cynthia Ramirez*Assistant Examiner* — Laura H Yu(57) **CLAIM**

The ornamental design for a shoe deodorizer, as shown and described.

DESCRIPTION

FIG. 1 is a top perspective view of a shoe deodorizer showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof; and,

FIG. 9 is a left elevated view thereof, showing the shoe deodorizer in an alternate, extended configuration.

The broken lines showing the ball strips in FIG. 1-2 and FIG. 5-9, and the broken lines showing a length-adjustment mechanism in FIG. 1-2 and FIG. 5-9, are included for the purpose of showing portions of the shoe deodorizer and form no part of the claimed design.

1 Claim, 9 Drawing Sheets
